UNITED STATES PATENT OFFICE.

HENRY R. BARNHURST, OF ERIE, PENNSYLVANIA.

SAW-MILL HEAD-BLOCK.

SPECIFICATION forming part of Letters Patent No. 281,750, dated July 24, 1883.

Application filed January 6, 1883. (No model.)

To all whom it may concern:

Be it known that I, HENRY R. BARNHURST, a citizen of the United States, residing at Erie, in the county of Erie and State of Pennsylvania, have invented certain new and useful Improvements in Saw-Mill Head-Blocks; and I do hereby declare the following to be a full, clear, and exact description of the invention, such as will enable others skilled in the art to which it appertains to make and use the same.

This invention relates to saw-mill head-blocks; and it consists in providing a construction whereby friction-roller bearings for the setting-shaft may be used in each of the blocks. This construction is especially desirable where the knees are reacted by springs, as is very common; but of course, whatever may be the construction or mode of operating the shaft, it is desirable that the friction of the shaft in its bearings in the blocks be as light as possible. When blocks have been in use a while they will become more or less loosened on the frame-work of the carriage, and then as a log is rolled onto them they get slightly out of line and bind on the shaft in the bearings, and by using friction-rollers in the bearings the bad effect of binding will be overcome very much.

30 The invention is illustrated in the accompanying drawings as follows:

Figure 1 is a side elevation of one of the blocks and knees, and shows the friction-rollers in place. Fig. 2 is a vertical transverse section on the line $x-x$ in Fig. 1. Fig. 3 is a perspective view with parts of the block and knee broken away so as to show internal construction.

40 Parts are indicated by letters of reference as follows: A is the block; C, the shaft; H, the pinion on the shaft which operates the knee. B is a large boss on the sides of the block which forms the chamber around the shaft for the friction-rollers to lie in. E are 45 the friction-rollers. G is a collar forming a

cap over the end of the boss, and serves to close the end of the friction-roller chamber, and g^2 are the screws for holding the said collar in place.

The construction is as follows: At the point 50 where the shaft passes through the block a circular opening is made which is as much larger than the shaft as is necessary to admit of rollers being placed therein all around the shaft. The walls of the block at this point 55 are made thicker by the boss B, so as to allow the use of rollers of considerable length. The rollers E, being in place, are retained from moving out of place lengthwise by the pinion H on one side and the collar G on the other side. 60 The collar G may be attached to the shaft, as is the pinion, or to the face of the boss, as it is shown to be in the drawings.

I have shown a system of rollers on each side of the block; but it is not necessary that 65 there should be.

I am aware that various kinds of journal-bearings have been provided with sets of friction-rollers substantially as in this instance, and I do not therefore desire to be 70 understood as claiming the use of friction-rollers in a journal-bearing, but simply as claiming the means herein shown for applying the said friction-rollers to the setting-shaft of a saw-mill head-block.

75 What I claim as new is as follows:

In a saw-mill head-block, the combination of the boss B, forming an annular chamber in the wall of said block around the shaft C, the rollers E, filling said chamber, and the collar 80 G and pinion H, closing the ends of said chamber, substantially as and for the purposes set forth.

In testimony whereof I affix my signature in presence of two witnesses.

HENRY R. BARNHURST.
